AUTOMOBILE SAFETY DOOR LOCK

Joseph M. Schumann, Inglewood, Calif.

Application January 4, 1954, Serial No. 28,333

Term of patent 3½ years

(Cl. D50—7)

Figure 1 is a front elevational view of an automobile safety door lock, with the lock member in unlocked position, showing my new design;

Figure 2 is a bottom plan view thereof, with the lock member in locked position;

Figure 3 is a top plan view thereof, with the lock member in locked position;

Figure 4 is a side elevational view thereof, with the lock member in locked position; and

Figure 5 is a rear elevational view thereof, with the lock member in locked position.

I claim:

The ornamental design for an automobile safety door lock, substantially as shown.
